AUTOMATIC SPEED REGULATOR FOR
TURBINES

Henry R. Tressl, Roundup, Mont.

Application July 2, 1948, Serial No. 36,758

4 Claims. (Cl. 253—24)

1

This invention relates to prime movers of the turbine type, and more particularly to automatic speed control means for a turbine.

A main object of the invention is to provide a novel and improved speed control means for a turbine; said speed control means being very simple in construction, reliable in operation, and very easy to adjust for obtaining the desired speed of operation of the turbine rotor.

A further object of the invention is to provide an improved turbine device of the automatic speed controlled type which accurately maintains its rotor speed substantially constant over a wide range of loading conditions, and which is particularly suitable for use with electrical generators, said turbine device involving only a few parts, being easy to adjust for obtaining a desired speed of rotor operation, being rugged in construction, and requiring only a minimum amount of human supervision.

Further objects and advantages of the invention will become apparent from the following description and claims, and from the accompanying drawings, wherein:

Figure 1 is a cross-sectional detail view with parts broken away, taken on line 1—1 of Figure 3 showing the turbine rotor and the speed regulating mechanism therefor.

Figure 2 is an enlarged cross-sectional detail view taken on line 2—2 of Figure 3.

Figure 3 is a side elevational view partly broken away of a turbine constructed in accordance with the present invention.

Figure 4 is a fragmentary side elevational view of the rotor and speed controlling mechanism therefor of the turbine of Figure 3 with the parts in positions corresponding to substantially no load on the turbine.

Figure 5 is a view similar to Figure 4 with the parts in positions corresponding to partial loading of the turbine.

Figure 6 is a view similar to Figure 4 with the parts in positions corresponding to full loading of the turbine.

Figure 7 is a view similar to Figure 4 but illustrating a modified form of speed-controlled turbine structure according to the present invention.

Figure 8 is a view generally similar to Figure 7 but illustrating still another form of speed-controlled turbine structure according to the present invention.

Figure 9 is a view generally similar to Figure 1 but showing a further form of speed-controlled turbine structure according to this invention.

2

Figure 10 is an enlarged cross-sectional detail view taken on line 10—10 of Figure 1.

Figure 11 is a side elevational view of the structure shown in Figure 9.

Referring to the drawings, and more particularly to Figures 1, 2 and 3, 11 designates a supporting frame which may be rectangular as shown, or may have any other suitable shape, and which includes a pair of parallel horizontal upper bar members 12, 12. Clamped transversely to the bar members 12, 12 by means of U-bolts 13, 13 is a sleeve member 14 in the respective end portions of which are secured the bearing bushings 15, 15. Journalled in bushings 15, 15 is a shaft 16, said shaft being provided with the end collars 17, 17 which rotatably engage the ends of sleeve member 14 and prevent shaft 16 from moving endwise. Secured to one end of shaft 16 is a pulley 18.

Designated generally at 19 is a fork member having depending arms 20 and 21, and having an upstanding intermediate arm 22. The arms 20 and 21 are formed at their upper ends with vertical slots 23, 23, and adjustably clamped to the arms at said slots by means of clamping bolts 24 are bearings 25, 25 rotatably mounted on the sleeve member 14. Secured on the sleeve member 14 outwardly adjacent to the respective bearings 25, 25 are stop collars 26, 26 which prevent the fork member 19 from moving longitudinally with respect to said sleeve member. The arms 20 and 21 are provided with adjusting screws 27, 27 abutting the bearings 25, 25 at the lower surfaces of said bearings for adjusting the bearings 25, 25 along the slots 23, 23.

Journalled in bearings 28, 28 secured to the lower portions of arms 20 and 21 is a shaft 29 which carries the turbine rotor 30, said rotor being substantially conventional in structure and having the peripheral arcuately curved impeller blades 31.

Secured to frame 11 is a shield 32 which covers the upper portion of rotor 30 and is suitably shaped to allow said rotor to swing through a substantial angle around the axis of shaft 16. Shaft 29 carries a pulley 33 which is coupled to pulley 18 by a crossed belt 34. Secured to shaft 29 outwardly adjacent the bearings 28, 28 are stop collars 35, 35 which prevent substantial endwise movement of said shaft. A guard housing 34' surrounds the pulleys 33, 18 and belt 34.

Secured to the top of frame 11 is a bracket member 36 formed with an offset top arm 37 opposing the upstanding arm 22 of fork member 19 and provided with an adjustable stop screw

38 engageable with arm 22. Designated at 39 is an upstanding bar member carried by frame 11, and connecting the top portions of arm 22 and bar member 39 is a spring 40 which biases fork member 19 clockwise, as viewed in Figure 3, so that arm 22 normally abuts the end of screw 38. Secured to the lower end of arm 21 of the fork member is a rearwardly extending bar 41 on which may be adjustably secured a weight 42, which also acts to bias fork 19 clockwise, as seen in Figure 3.

Secured in the lower portion of frame 11 is a nozzle 43 which is preferably rectangular in cross section and which is directed toward the bottom impeller blades 31 of rotor 30 so as to impart counterclockwise rotation to the rotor as viewed in Figure 3, when a fluid jet is discharged therefrom. In the normal position of fork 19, with arm 22 abutting the end of screw 38, only the upper portion of the jet engages the impeller blades 31. The axis of the nozzle is upwardly inclined to a position, substantially tangential to rotor 30 in its normal position. As the fork 19 swings counterclockwise around the axis of shaft 16, as viewed in Figure 3, the lower portion of rotor 30 is brought more and more into the path of the fluid jet emerging from nozzle 43 due to the fact that the radial distance from the bottom peripheral portion of rotor 30 to the axis of shaft 16 is much greater than the radius of the rotor 30.

Shaft 16 is connected to a suitable load, as for example, a generator 44, as shown in Figures 4, 5 and 6. Figure 4 shows the positions of the parts at no load. The nozzle jet, indicated at 45, only partially engages the impeller blades of the rotor 30 but furnishes enough energy to revolve the rotor, since the resistance to rotation thereof is quite small. As load is applied to generator 44, the resistance to rotation developed in rotor 30 increases, and the jet 45 provides a force sufficient to overcome the biasing force of spring 40, the moment between the jet and the axis of shaft 16 overcoming the restraining moment of said spring. This causes the fork 19 to swing counterclockwise from the position of Figure 4 to the position of Figure 5, carrying the rotor 30 to a position wherein an increased cross-sectional area of the jet is engaged by the rotor blades. Since the force applied to the rotor blades by jet 45 is proportional (at constant fluid pressure) to the area of the jet acting on the blades, the torque applied to rotor 30 is increased, thereby compensating for the increased loading of the generator without reducing the rotational speed of the rotor. As the generator load is increased to full load, fork 19 is swung further counterclockwise due to the increase in resistance to rotation of rotor 30, to the position of Figure 6 wherein the entire cross-sectional area of the jet 45 acts on the impeller blades of the rotor. The increased torque on the rotor again compensates for the increased loading of the generator, and the rotor speed remains substantially unchanged. As the loading on the generator decreases, the spring 40 returns the fork 19 to that position wherein the jet area engaging the impeller blades provides sufficient force to rotate rotor 30 under its load and to balance the moment exerted on fork 19 by the spring 40.

From the above discussion, it will be apparent that for a constant fluid pressure at jet 45, the rotor speed at no load may be set by adjusting the stop screw 38 so that the jet 45 just engages the blades of the rotor 30. The amount of torque compensation provided under loading conditions

will then depend upon the strength of spring 40 as well as upon the relative radial distances of spring 40 and the lower peripheral portion of rotor 30 from the axis of shaft 16. By a proper choice of spring 40 the rotational speed of rotor 30 between no load and full load conditions may be therefore held constant.

Secured to the top of frame 11 on the opposite side of arm 22 from bracket member 36 is a second upstanding bracket member 36' provided with a stop screw 38' engageable by arm 22 to limit counterclockwise rotation of fork member 19. Stop screw 38' is employed to prevent rotor 30 from engaging shield 32 when the turbine is overloaded.

Oscillations of fork 19 around its equilibrium position for a given condition of loading are damped by means of a damping collar comprising arcuate segments 46 and 47 hinged together at 48 and encircling the intermediate portion of sleeve member 14. The segments 46 and 47 are formed with opposing lug portions 49 and 50 and a screw bolt 51 passes through lug portion 49 and threadedly engages lug portion 50. Encircling screw bolt 51 and bearing between the head of said bolt and the lug 49 is a coiled spring 52, which provides a frictional gripping force of the segments 46 and 47 on the sleeve member 14. Segment 46 is formed with an upstanding tapped lug 53 through which a stop screw 54 is threaded, said stop screw being engageable with fork 19. Segment 47 is formed with a depending lug 55 provided with an adjustable stop screw 56 also engageable with fork 19. Angular movement of fork 19 with respect to sleeve member 14 is damped by the frictional engagement of segments 46 and 47 with said sleeve member, the degree of damping being adjustable by means of screw bolt 51 and the amount of undamped permissible movement of fork 19 being adjustable by means of stop screws 54 and 56.

If the embodiment illustrated in Figure 7, the shaft 16 carries a sprocket 57 and shaft 29 carries a sprocket 58. Secured to fork 19 adjacent sprocket 58 is a plate member 59 on which is rotatably mounted an idler sprocket 60. A sprocket chain 61 extends around sprocket 57 and idler sprocket 60, meshing with sprocket 58, as shown in Figure 7. Pivotally connected to the lower end of fork arm 21 is a link rod 62. Designated at 63 is a control valve interposed in the nozzle conduit 43, said valve having an operating lever 64 which is pivotally connected to link rod 62. Valve 63 is normally open only partially and gradually becomes further open when lever 64 is rotated clockwise from the position shown in Figure 7. In this embodiment the nozzle 43 is inclined upwardly at a steeper angle than in Figure 4 and is arranged so that the full cross-sectional area of the nozzle jet impinges on the rotor blades at all times, but the jet flow rate is regulated by valve 63. Under no load conditions, the rate of flow is low. As the load increases, fork 19 swings counterclockwise in the manner previously described, whereby link rod 62 rotates valve lever 64 clockwise, causing the flow rate to increase and increasing the torque applied to the rotor. The turbine is thus enabled to sustain the increase in loading without reducing its speed. As in the previous embodiment of the invention, the speed may be held constant between no load and full load conditions by a proper choice of biasing spring 40.

In the embodiment of Figure 8, shaft 16 carries a gear 65 which directly meshes with a gear

66 carried by shaft 29. The nozzle 43 is arranged in the same manner as in the embodiment of Figures 1 to 6 and the operation of the turbine is the same as in said former embodiment, the turbine rotor blades being engaged only partially by the nozzle jet at no load and being fully engaged by said jet at full load, the spring 40 regulating the equilibrium speed of the turbine rotor over the range of different loading conditions, whereby the speed may be held constant by a proper choice of spring.

In the embodiment of Figure 9, the turbine rotor 39 is mounted separately from the speed regulating mechanism and is journaled in upstanding supports shown at 61, 61. The speed regulating mechanism comprises a frame 68 which is pivotally mounted on a horizontal sleeve member 14, said sleeve member being clamped to a suitable support, not shown. The shaft 16 is journaled in sleeve member 14 and carries a pulley 18 coupled by a crossed belt 34 to the pulley 33 carried on a shaft 29 journaled in the lower portion of frame 68. The rotor shaft, shown at 69, is connected by a universal joint 70 to a spline rod 71 which is slidably received in an internally splined sleeve member 72. Sleeve member 72 is connected by a universal joint 73 to the end of shaft 29. The nozzle conduit, shown at 74 includes a flow control valve 75 having an operating lever 76. Lever 76 is connected by a link bar 77 to the lower end of frame 68. Frame 68 is formed with an upstanding arm 22'. Connected to the top end of arm 22' is the speed regulating spring 40, which functions in the same manner as in the embodiment of Figure 7 to bias the valve 75 toward a partly closed position. As in Figure 7, the nozzle 43 is arranged so that the turbine blades are engaged by the full cross-sectional area of the nozzle jet at all times. When there is no load on the generator 44, reduced flow occurs at the nozzle 43. When the load on the generator is increased, demanding more torque on the rotor blades, the rotor slows down momentarily, allowing increased torque to be developed at shaft 29, said increased torque creating a moment on frame 68 with respect to the sleeve 14 which overcomes the biasing moment of spring 40 and rotates frame 68 to a position opening valve 75 more fully. This increases the flow at jet 43 and provides the necessary increased torque on the rotor blades to restore the turbine to its desired speed. As in the embodiments previously described, the steady state speed of the turbine rotor may be controlled and held constant by a proper choice of spring 40.

While certain specific embodiments of automatic speed regulating mechanism for turbine rotors have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In combination, a turbine rotor, a frame, a support, means swingably mounting said frame with respect to said support, means rotatably mounting said rotor on said frame for swinging movement therewith on an axis offset from the swinging axis of the frame, a shaft journaled

in said frame, coaxially with said swinging axis, a stationary nozzle furnishing fluid to the periphery of said rotor and including a flow-controlling valve, means linking said frame to said valve, means biasing said frame to a position partially closing said valve, whereby a relatively small amount of fluid flow normally occurs in the nozzle, and means coupling said rotor to said shaft.

2. In combination, a turbine rotor, a frame, a support, means swingably mounting said frame with respect to said support, means rotatably mounting said rotor on said frame for swinging movement therewith on an axis offset from the swinging axis of the frame, a shaft journaled in said frame, coaxially with said swinging axis, a stationary nozzle furnishing fluid to the periphery of said rotor and including a flow-controlling valve, means linking said frame to said valve, means biasing said frame to a position partially closing said valve, whereby a relatively small amount of fluid flow normally occurs in the nozzle, means coupling said rotor to said shaft, and adjustable damping means frictionally secured on said support and engaging said frame, said damping means preventing free oscillation of said frame.

3. In combination, a turbine rotor, a frame, a support, means swingably mounting said frame with respect to said support, means rotatably mounting said rotor on said frame for swinging movement therewith on an axis offset from the swinging axis of the frame, a shaft journaled in said frame coaxially with said swinging axis, a stationary nozzle furnishing fluid to the periphery of said rotor and including a flow-controlling valve, means linking said frame to said valve, means biasing said frame to a position partially closing said valve, whereby a relatively small amount of fluid flow normally occurs in the nozzle, and positive drive means coupling said rotor to said shaft.

4. In combination, a turbine rotor, a frame, a support, means swingably mounting said frame with respect to said support, means rotatably mounting said rotor on said frame for swinging movement therewith on an axis offset from the swinging axis of the frame, a shaft journaled in said frame coaxially with said swinging axis, a stationary nozzle furnishing fluid to the periphery of said rotor and including a flow-controlling valve, means linking said frame to said valve, means biasing said frame to a position partially closing said valve, whereby a relatively small amount of fluid flow normally occurs in the nozzle, respective sprockets secured to said rotor and said shaft, and a sprocket chain engaged on said sprockets.
